UNITED STATES PATENT OFFICE.

JAMES A. DUNNING, OF AULANDER, NORTH CAROLINA, ASSIGNOR OF ONE-HALF TO ROBERT J. DUNNING, OF SAME PLACE.

COLLAR-BUTTON SHIELD.

SPECIFICATION forming part of Letters Patent No. 541,809, dated June 25, 1895.

Application filed January 24, 1895. Serial No. 536,067. (No model.)

To all whom it may concern:

Be it known that I, JAMES A. DUNNING, a citizen of the United States, and a resident of Aulander, in the county of Bertie and State of North Carolina, have invented certain new and useful Improvements in Collar-Button Shields; and I do declare the following to be a full, clear, and exact description of the invention, such as will enable others skilled in the art to which it appertains to make and use the same, reference being had to the accompanying drawings, and to letters of reference marked thereon, which form a part of this specification.

15 Figures 1 and 2 of the drawings are representations of the invention applied. Fig. 3 is a side view of the invention applied. Fig. 4 is a perspective view of the invention. Fig. 5 illustrates method of manufacturing shields.

20 The object of this invention is to provide means of improved character for use in connection with collar buttons for the purpose of relieving the neck of the wearer from the pressure and irritation of the button.

25 As is well known, the ordinary collar buttons are a source of great discomfort by reason of their action upon the flesh at the back of the neck, often resulting in serious sores the danger and discomfort of which are increased

30 by the liability of poisoning from the brass or other metal of the button. This is entirely obviated by the present invention, which provides a shield capable of being applied to the various forms of buttons commonly in use, 35 and which can be manufactured and sold at a very small cost.

With this object in view, the invention consists in the novel construction and combination of parts, all as hereinafter described and 40 pointed out in the appended claim.

The invention more particularly consists in a shield constructed of two superimposed flexible disks A and B, of suitable form and of a diameter appreciably greater than the 45 base of the button, secured to each other by stitching or cement, the upper one having therein a central aperture a, to each side of which extends a narrow slit b. The central aperture a receives the shank of the button,

while the radial slits b permit the insertion of 50 the base between the two disks, after which the upper disk closes down upon and covers said base. In securing the disks together, they are stitched or cemented at the marginal portion only, and they are left unsecured at 55 opposite sides, as indicated at c, c, for the purpose of allowing them to spring or yield apart at these points to facilitate the insertion of the button base. The disks may be made of any material suitable for the purpose, sheep 60 skin, kid, or other kinds of soft leather being excellent.

In manufacturing the shields, I take two narrow strips P, P' of the material, the upper of which has the apertures a, and the slits b cut 65 therein, and secure them together along their longitudinal margins by stitching or cement, as indicated in Fig. 5. From this the shields are cut by a suitable die or cutter. Each shield so cut has the disks unsecured 70 upon two opposite sides, as above described.

It will be apparent that this shield forms an efficient protector for the tender parts upon which the base of the button commonly bears, and saves the wearer all discomfort therefrom. It also serves to hold the stiff collar band away from the back of the neck which is often another source of discomfort. 75

Having thus described my invention, what I claim as new, and desire to secure by Letters 80 Patent, is—

As a new article of manufacture, the herein described shield for collar buttons, consisting of two superimposed soft and thin flexible disks of greater diameter than the base of the 85 button, and secured to each other at their marginal portions only, said marginal portions being left unsecured at opposite points, and slits in the upper of said disks to admit the base and shank of the button, substantially as specified. 90

In testimony whereof I affix my signature in presence of two witnesses.

JAMES A. DUNNING.
